COMBINATION SOFA AND TABLE

John M. Schenzinger and Warren Baicher,
Altadena, Calif.

Application March 3, 1950, Serial No. 147,446

2 Claims. (Cl. 155—123)

1

This invention relates to the class of furniture and is directed particularly to a combined sofa and table structure.

A particular object of the present invention is to provide, in combination, a sofa structure and a foldable table, wherein the sofa is constructed with a recess or chamber in the arm and the table has foldable leaves and is designed, when folded to be inserted into such recess, with a part of the table serving as a closure panel for the recess when the table is housed therein.

Another object of the invention is to provide a combination structure of the character above set forth, wherein a novel mechanism is provided for latching or securing the folded table in the recess and for effecting its release and partial ejection therefrom, when desired for use.

Other objects and advantages of the invention will become apparent as the description of the same proceeds and the invention will be best understood from a consideration of the following detailed description taken in connection with the accompanying drawing forming a part of the specification, with the understanding, however, that the invention is not to be limited to the exact details of construction shown and described since obvious modifications will occur to a person skilled in the art.

In the drawing:

Figure 1 is a view in perspective of a combination sofa and table constructed in accordance with the present invention, showing the table drawn out and set-up for use.

Figure 2 is a vertical section through the arm of the sofa, from the front to the rear, showing the folded table housed therein.

Figure 3 is a sectional view taken substantially on the line 3—3 of Figure 2.

Referring more particularly to the drawing the numeral 10 generally designates a sofa of a type having end arms 11 of full height and of substantial thickness.

In accordance with the present invention one of arms 11, here shown as the right arm, is constructed in hollow form to provide a recess or chamber 12, and the front of the arm has an opening 13 through which the hereinafter described foldable table may be inserted and withdrawn.

The table is generally designated 14 and as shown comprises a vertical square body frame 15 consisting of the top and bottom horizontal rails 16 and 17 respectively and the front and rear vertical rails 18 and 19 respectively.

The front rail 18 has secured thereto the ver-

2

tical closure or door panel 20 which fits in the opening 13 when the table is housed. This panel 20 additionally functions as a front leg, having its lower end extended for this purpose below the bottom rail 17, as shown in Figure 2.

Cooperating with the bottom end of the panel 20, to support the back part of the table, is a caster wheel 21 which is secured to the under side of the bottom rail at the back end thereof and runs upon the bottom or floor 12a of the chamber.

Disposed horizontally upon the top rail 16 is the fixed center leaf 22 of the table top. The forward end of this leaf joins the top of the face panel 20 and the back end extends rearwardly beyond the frame 15 and is bifurcated to provide the slot 23.

The arm 11 also includes the top wall 12b and at its front end is a depending flange or lip 13a which forms the top edge of the opening 13.

The under face of the top wall 12b has formed therein the longitudinally extending guide groove 24.

Fixed to and upon the top of the center leaf 22, at the rear end thereof, is a guide lug 25 which slidably engages in the groove 24. The forward travel of this lug 25 in the groove 24, when the table is drawn out, is limited by the lip 13a.

Hinged to each side edge of the top center leaf, by hinges 26, is a wide drop leaf 27. These drop leaves are supported horizontally in the plane of the center leaf 22, each by a leg 28 which has rigidly secured to it at the top and bottom the arms 29 and 30 respectively. These arms are hinged to the top and bottom frame rails as at 31 to swing on a vertical axis whereby the leg may be closed against the side of the frame or swung outwardly therefrom as shown in Figure 1.

As shown in Figure 2 the depth of the chamber 12 is considerably greater than the length of the frame 15 so that when the table is within the chamber the back rail 19 is spaced from the back wall 12c.

Secured to the back wall 12c just below the bifurcated end of the center leaf is a vertical guide 32, through which extends the latch pin 34.

The top wall 12b, above the guide 32, has an opening 35, in which is located a button 36 which is carried upon the top end of the pin 34. The pin enters the slot 23 in the back end of the center leaf, as shown, when the table is housed.

Below the pin 34, the back wall 12c has

mounted thereon a bracket 37 to which is pivotally connected to swing on a horizontal pivot 38, an upwardly and forwardly extending leg 39.

The numeral 40 designates a latch bolt which is mounted on the leg 39 by the upwardly and rearwardly inclined arm 41. This arm 41 is directly beneath and engaged, rearwardly of the forward end of the leg 39, by the lower end of the pin 34. This contact of the bolt arm 41 with the end of the pin holds the bolt against swinging on the pivot 38 beyond the vertical, downwardly directed position shown. To urge this swinging of the bolt at all times, however, a spring 42 is connected between the leg 39 and the bracket 37 below the pivot as shown.

Upon the back edge of the back rail 19 is secured, at the proper height with respect to the bolt 40, a keeper tongue 43 which stands upright in spaced relation to the adjacent rail. The bolt engages the keeper 43 upon the front side to hold the table in the chamber and the bolt and keeper have chamfered striking faces 44 and 45, as shown, whereby the same will be automatically coupled when the folded table is shoved into the chamber 12.

Below the latching mechanism the back wall 12c has fixed thereto at the points 46, the two ends of an arcuate or bowed spring 47, the arc or bow of which is directed forwardly. This spring may be of any suitable form, but is here shown as comprising a length of suitable spring wire bent in a series of reversed loops. When the table is fully within the chamber the rail 19 will press against the bow of the spring and flatten the same, as shown, thus putting the spring 35 under tension.

When the table is to be removed from the chamber a downward pressure upon the button 36 presses the stem 34 down upon the bolt arm 41 to oscillate the bolt out of engagement with the keeper. The spring 47 will then eject the table sufficiently so that the front panel may be grasped and the table drawn out to the full extent to permit the side leaves to be raised.

When the table is folded and shoved back into the chamber the bolt will automatically engage the keeper, as will be readily apparent.

We claim:

1. In an article of furniture having an arm, a chamber in the arm having a front opening, the chamber having top, bottom and back walls, a foldable table comprising an upright frame adapted to be inserted into the chamber through said opening, the table including a narrow central leaf supported upon the top of the frame and side drop leaves hinged to the central leaf, a front closure panel secured to the frame and fitting in and closing said opening when the folded table is in the chamber, said panel being extended down below the frame to provide a front table leg, a roller supporting the rear of the frame upon said bottom wall, a guide means between the central leaf at its rear end and said top wall, releasable latching means coupling the frame with said back wall when the folded table is within the chamber, and resilient means for ejecting the table from the chamber upon release of the latching means.
2. An article of the character set forth in claim 1, wherein said latching means comprises a keeper carried upon the rear of the frame, a pivot bolt mounted upon the back wall of the chamber, an inwardly and rearwardly inclined arm carried by the bolt, a vertically reciprocable pin disposed above and having its lower end engaging the top of said arm and a button upon the top of said pin, the top wall having an opening for the button to facilitate application of downward pressure thereon.

JOHN M. SCHENZINGER.

WARREN BAICHER.
